UNITED STATES PATENT OFFICE.

JOSEPH HALE, OF SOMERVILLE, MASSACHUSETTS.

IMPROVEMENT IN SCROLL-SAWING MACHINES.

Specification forming part of Letters Patent No. **160,768**, dated March 16, 1875; application filed March 20, 1874.

To all whom it may concern:

Be it known that I, JOSEPH HALE, of Somerville, in the county of Middlesex and State of Massachusetts, have invented certain new and useful Improvements in Scroll-Sawing Machine, of which the following is a specification:

The nature of my invention consists in combining with the swinging arms of a fret-saw slides working in fixed grooves, said slides serving to hold the saw, and thus directing its motion; also, in arranging one of the slides so that it may be strained up to make the saw taut.

The drawing represents the invention in elevation.

Let S represent the driving-wheel, from which a band connects with the crank-disks K. On this crank-disk I place a crank-pin, m, which, working through a slot, L L', in the arm E, operates said arm. The arm E is connected by a link, H, to the upper arm D, so that the arms E and D must operate together. A and A' is a fixed frame, made as shown.

In the extremities of the arms of this fixed frame I hang the slides P P', which work in fixed grooves. These slides P P' hold the ends of the saw, and are attached to the oscillating arms E and D by the links R and R', as shown, so that the saw may have a perfectly vertical motion. The upper link R' is connected to an adjustable rod, T, which is held at the desired point by the set-nut T'.

The advantage that I claim for my invention is that I get a perfectly vertical motion by a very simple and cheap device.

I claim as my invention—

In a fret-saw, the combination of the crank K M, slotted arm E, link H, and arm D with the links R R', slides P P', and adjusting-rod T, all constructed and operating together, substantially as described, and for the purpose set forth.

JOSEPH HALE.
